UNITED STATES PATENT OFFICE.

HOWARD EARL HOOVER, OF CHICAGO, ILLINOIS, ASSIGNOR TO THE HOOVER SUCTION SWEEPER COMPANY, OF NEW BERLIN, OHIO, A CORPORATION OF OHIO.

DESIGN FOR A BAG FOR SUCTION-SWEEPERS.

53,222.

Specification for Design. Patented Apr. 22, 1919.

Application filed June 3, 1918. Serial No. 238,055. Term of patent 14 years.

To all whom it may concern:

Be it known that I, HOWARD EARL HOOVER, a citizen of the United States, residing at Chicago, in the county of Cook and State of Illinois, have invented a new, original, and ornamental Design for Bags for Suction-Sweepers, of which the following is a specification, reference being had to the accompanying drawing, forming a part thereof.

Fig. 2 is an end view of the bag.

I claim:
The ornamental design for a bag for suction sweepers as shown.

HOWARD EARL HOOVER.

Witnesses:

LAUREL D. MEYER,
MARION L. INGRAHAM.
